Atty.

UNITED STATES PATENT OFFICE.

EDWARD JAMES WILD, OF CAMDEN TOWN, ENGLAND, ASSIGNOR TO CHARLES NORMAN GARNER, OF TOTTERIDGE, HERTFORD, ENGLAND.

COLLAPSIBLE BOX.

1,356,681.

Specification of Letters Patent. Patented Oct. 26, 1920.

Application filed January 2, 1917. Serial No. 140,234.

To all whom it may concern:

Be it known that I, EDWARD JAMES WILD, a subject of the King of Great Britain and Ireland, and residing at 1 St. Paul's Crescent, Camden Town, in the county of Middlesex, England, have invented certain new and useful Improvements in Collapsible Boxes, of which the following is a specification.

- 10 This invention relates to improvements in collapsible boxes.
According to this invention the collapsible box comprises a bottom to which is hinged sides furnished at each upper corner with 15 a pivoted stud adapted to engage two ends hinged to said bottom. A lid having a binding forming a downwardly projecting flange is adapted to embrace the side and the ends and means are provided for connecting the lid and the ends in the set-up condition as well as means for connecting the lid to the bottom in the folded condition, the lid being for that purpose removed and inverted, having the bottom with the sides 25 and ends folded thereon laid in the top.

In the accompanying drawings—

Figure 1 is a longitudinal vertical section of a box embodying my invention.

Fig. 2 is a plan view with the lid re-30 moved.

Fig. 3 is a vertical cross section.

Fig. 4 is a perspective view showing the box in the folded condition.

Figs. 5 and 6 are elevation and plan re-35 spectively of connecting studs on a larger scale.

Fig. 7 is an enlarged detail sectional view of a connection for the lid.

Fig. 8 is an end elevation of same, and

40 Fig. 9 shows the same in section when the box is folded.

In said drawings the sides 102, as well as the ends 103 are hinged to the bottom 101. The sides are hinged at 105 and 106, respectively, to the bottom. The pivots of the hinges 105 are in the angle formed by one side and the bottom, but the hinges 106 are bent as seen in Fig. 3 so that their pivot pins are above the level of the bottom and thus one side 102 is adapted to fold down flat onto the bottom, while the other side folds down onto the first mentioned side and approximately parallel thereto as seen in Fig. 4. The ends 103 are hinged at 133, 55 in such a manner, to the bottom 101 as to

fold down underneath the latter in the collapsed condition, the pivots 133 being approximately in the same plane as the lower side of the bottom and of such a length as to allow the ends 103 to rest on the extremities of the bottom when the box is erected. 60

The ends 103 are preferably furnished with a metal binding 11, 12, (Figs. 5 and 6) which is angular in cross section and suitably fixed to the ends. Sufficient space is 65 left between the projecting portion 12 and the edge of the ends 103 to form a housing to receive the sides 102 as shown in Fig. 6. The member 11 is moreover provided with a recess 14 in the top between the end 103 70 of the box and the projecting member 12, said recess 14 being adapted to take a stud 120 provided on each end of the sides 102 near the top thereof.

The stud 120, as shown on an enlarged 75 scale in Figs. 5 and 6, comprises a flat head 20 which may be round or rectangular at each side and furnished with a curved or bent, flat shank 21 perforated near the end remote from the head. The studs 120 are 80 pivotally connected to the sides 102 of the box near the corners by screws 22 and are adapted to be swung so that the shanks of the studs pass into the recesses 14 in the binding with the head outside the recess. 85

In order to tighten the ends and sides and to improve the rigidity of the box, the parts of the head come into contact with the outer face of the binding and are made sloping at 23 (Fig. 5) so as to facilitate 90 the setting up of the box and to exert a wedging action which results in drawing the sides and ends of the box together.

The lid 104 is surrounded or bound as clearly shown in Fig. 4, by an angular 95 metal binding 31 forming a depending flange which extends down over the studs 120 when the box is set up.

The side 102 that lies on top when the box is folded (see Figs. 4 and 9), is provided at each extremity with a nut 145 in which engages a screw 135 passing through a link 142 pivotally mounted on the flange 31 of the lid 104 for normally holding one of the sides 102 onto the bottom 101 when the box is collapsed, so that the bottom, sides and ends of the box are entirely contained in and positively connected to the lid 104 when folded. 100

To secure the top in place, when the box 110

is erected, a nut 36 (Fig. 7) is fixed in a hole in each end 103 of the box at some distance from the top thereof and secured by a plate 41, or by two such perforated plates, 5 one on each side nailed or riveted to the ends of the box and the screw 135 passes through the link 142 (pivoted at 43 to the binding 31 of the lid) and into said nut 36.

I claim—

- 10 1. A collapsible box comprising a bottom, two sides hinged one to the bottom with the axis of its hinges in the same plane as the top of the said bottom and the other with the axis of its hinges in a plane situated above the bottom at a distance equivalent to the thickness of a side so that one side may be folded flat onto the bottom and the other side may be folded flat onto the aforesaid side, a nut mounted in each end 15 of the side hinged at a distance from the bottom, two ends hinged to the said bottom and adapted to be folded down and underneath the bottom, studs pivoted on the sides adapted to engage and project over the 20 ends, a detachable lid, an angular metal binding surrounding said lid to form a depending flange to embrace the sides and ends and the studs, a perforated link pivoted to each end of the metal binding of 25 the lid, a nut in each end, and a screw passing through each pivoted link to engage the nut in each end when the box is in the erected condition and adapted to engage in the nut in each end of said side when the 30 ends have been folded flat under the bottom and the sides have been folded superposed on the upper side of the bottom and the bottom with the ends and sides have been laid in the lid of the box.
- 40 2. A collapsible box comprising a bottom, two sides hinged to the bottom, one with the axis of its hinges in the same plane as the top of the said bottom and the other with the axis of its hinges in a plane situated above the bottom at a distance equivalent to the thickness of a side so that one side may be folded flat onto the bottom and the other side may be folded flat onto the aforesaid side, a nut mounted in each end 45 of the side hinged at a distance from the bottom, two ends hinged to the said bottom and adapted to be folded down and underneath the bottom, studs pivoted on the sides and having wedge-shaped heads 50

adapted to take over and engage the ends 55 when erected, a detachable lid, an angular metal binding surrounding the lid to form a depending flange to embrace the sides, ends and the studs, a perforated link pivoted to each end of the metal binding of 60 the lid, a nut in each end and a screw passing through each pivoted link to engage the nut in each end when the box is in the erected condition and adapted to engage the nut in each end of said side when the ends 65 have been folded flat under the bottom and the sides have been folded superposed on the upper side of the bottom and the bottom with the ends and sides have been laid in the lid of the box.

70 3. A collapsible box comprising a bottom, two sides hinged to the bottom, one with the axis of its hinges in the same plane as the top of the said bottom and the other with the axis of its hinges in a plane situated above the bottom at a distance equivalent to the thickness of a side so that one side may be folded flat on to the bottom and the other side may be folded flat onto the aforesaid side, a nut mounted in each end 75 of the side hinged at a distance from the bottom, two ends hinged to the said bottom and adapted to be folded down and underneath the bottom, metal binding secured at the side edges of the ends and 80 provided with recesses, studs pivoted on the sides and movable into said recesses when the box is erected, wedge-shaped heads on said studs adapted to engage the outer face of said metal binding when said 85 studs are moved into said recesses, a detachable lid, an angular metal binding surrounding said lid to form a depending flange to embrace the sides, ends and the 90 studs, a perforated link pivoted to each end of the metal binding of the lid, a nut on each end, and a screw passing through each pivoted link to engage the nut in each end when the box is in the erected condition and 95 adapted to engage the nut in each end of said side when the ends have been folded flat under the bottom and the sides have been folded superposed on the upper side of the bottom and the bottom with the ends and sides have been laid in the lid of the 100 box.

105 EDWARD JAMES WILD.
